UNITED STATES PATENT OFFICE.

DANIEL M. MAHANEY, OF NEW YORK, N. Y.

SUPPLEMENTAL OILER FOR JOURNALS.

1,309,864.

Specification of Letters Patent. Patented July 15, 1919.

Application filed December 3, 1918. Serial No. 265,142.

To all whom it may concern:

Be it known that I, DANIEL M. MAHANEY, a citizen of the United States, and residing at New York, in the county of New York 5 and State of New York, have invented certain new and useful Improvements in Supplemental Oilers for Journals, of which the following is a specification, such as will enable those skilled in the art to which it applies 10 to make and use the same.

This invention relates to the oiling mechanism of the journals of railway wheel shafts, axles or the like, and particularly to oiling mechanisms of this class in the form 15 of boxes in which the journals are mounted; and the object of the invention is to provide a supplemental means which is automatic in operation for oiling such journals when the oil in said boxes is consumed and 20 to re-oil said journals before they become what is known as hot-boxes caused by the lack of lubrication; and a further object of the invention is to provide a supplemental oiling mechanism of the class and for the 25 purpose specified which is simple in construction and operation and efficient in use.

The invention is fully disclosed in the following specification, of which the accompanying drawing forms a part, in which the 30 separate parts of my improvement are designated by suitable reference characters in each of the views, and in which:—

Figure 1 is a side diagrammatic view of a truck of a railway car and indicating my 35 improvement connected therewith;

Fig. 2 a partial section on the line 2—2 of Fig. 1 on an enlarged scale and with parts in a different position; and,

Fig. 3 a partial section on the line 3—3 40 of Fig. 2.

In Fig. 1 of the drawing I have shown at 10 one form of truck usually employed for supporting a railway car, the opposite ends of the truck being provided with boxes 11 45 in which the journals 12 are mounted, said journals being on the ends of the axles carrying the wheels 13 of the truck 10. The end of each of the journals is flanged as shown at 14, and mounted in the top of the boxes 50 11 and resting upon the top of the journals 12 are the usual brasses 15 which take the thrust of the load upon the journals 12 in the usual manner. The outer portions of the boxes 11 are made hollow in form as 55 shown at 16 and provided with openings 17 which are normally closed by covers 18.

The above described construction is similar to that common in apparatus of the class specified and forms no part of my invention and has been merely shown to illustrate 60 one use of my improvement and, in practice, I provide the inner face of the cover 18 with a reservoir 19 which may be secured thereto, or formed integral therewith, and connected with one side of the reservoir 19 65 at the bottom thereof is a pipe 20 which extends backwardly into the box 11, and is provided on its inner end with a valve device 21, the discharge 22 of which is directed at right angles to the pipe 20, and in the 70 direction of the journal 12. The valve 21 is normally closed but may be opened by depressing a headed plunger 23 in the top thereof.

I also provide a spring arm 24 which is 75 secured to the inner face of the box 11 and in such position as to permit the arm 24 to strike the headed plunger 23, and said arm is normally held in a raised position by a wire or cable 25 which passes around a pulley 26 pivoted to the wall of the box 11 as shown in Fig. 3, said wire being passed through an aperture 27 in the brass 15 at the top of the journal 12, and the end thereof connected with a small piece of Babbitt or 80 similar material 28 on the inner arc-shaped face of the brass 15, and which has a bearing 85 on the outer face of the journal 12.

The piece of Babbitt or other metal serves 90 to retain the wire or cable 25 in connection with the brass 15 and to support the spring arm 24 in position shown in Fig. 3, and when oil in the box 11 has been consumed or the journal 12 is in need of lubrication, the heat generated by the friction between the brass 95 15 and journal 12 due to lack of lubrication will melt or break up the piece of Babbitt or similar metal 28 thus causing the release of the wire or cable 25, which permits the descention of the spring arm 24, 100 and this operation depresses the headed plunger 23 and opens the valve 21 to allow the oil in the reservoir 19 to be discharged into the box 11 and onto the journal 12.

The bottom of the reservoir 19 is prefer- 105 ably graded as shown at 29 in Fig. 1, and a plug 30 is connected with the bottom of the reservoir to permit of the filling of said reservoir whenever desired. It will also be noted that the reservoir 19 with the pipe 110 20 and valve 21 are carried by the cover 18 of the box 11 and the parts which operate

the valve 21 are carried by or mounted in the box 11 and brass 15; and while I have shown certain details for carrying my invention into effect it will be understood that 5 various changes therein and modifications thereof may be made, within the scope of the appended claims, without departing from the spirit of my invention or sacrificing its advantages.

10 Having fully described my invention, what I claim as new and desire to secure by Letters Patent, is:—

15 1. A supplemental oiler for journals of the class described mounted in journal boxes having the usual brasses and pivoted covers, said oiler comprising a reservoir mounted on the inner face of the cover of said box, a discharge pipe connected with said reservoir and a valve in said pipe, said valve being normally closed, means secured to the box in juxtaposition to said valve for opening the same, and means involving a fusible device secured in the inner face of the brass of the journal for holding said first named 25 means in an inoperative position.

20 2. The combination with apparatus of the class specified, comprising a journal mounted in a journal box having a pivoted cover and a brass, of a supplemental oiler comprising a reservoir mounted on the inner face of the cover of said box, said reservoir being provided with a discharge valve which is normally closed, tensional means 30 mounted in said box in juxtaposition to said valve for opening the same, and means in-

volving a fusible device secured in the bearing face of said brass for holding said first named means in an inoperative position.

3. The combination with an apparatus of the class specified, comprising a journal mounted in a journal box having a pivoted cover and a brass, of a supplemental oiler comprising a reservoir mounted on and movable with the cover of said box, said reservoir being provided with a discharge pipe having a valve which is normally closed, means for supplying oil to said reservoir, a spring arm secured to the box in juxtaposition to and independent of said valve and adapted to open the same, a wire or cable connected with the free end of said arm, said wire or cable being passed around a pulley secured in the box and the end thereof secured in the inner or bearing face of said brass by a piece of Babbitt metal 55 which has a bearing on said journal whereby when the journal becomes heated said Babbitt metal will be melted or broken up to release said wire or cable and said spring arm to permit the opening of said valve to discharge the oil in said reservoir into said box to lubricate the journal.

In testimony that I claim the foregoing as my invention I have signed my name in presence of the subscribing witnesses this 2nd day of December, 1918.

DANIEL M. MAHANEY.
